(57) **CLAIM**

The ornamental design for a light fixture, as shown and described.

DESCRIPTION

FIG. 1 is a front perspective view of the light fixture comprising my new design;

FIG. 2 is a front elevational view thereof;

FIG. 3 is a side elevational view thereof which is an identical mirror image of the other side;

FIG. 4 is a top plan view thereof; and,

FIG. 5 is a bottom plan view thereof.

FIG. 1-FIG. 5 showing chains of translucent crystals defining arcs in space and crystal drop ornamentation.

The broken lines shown are for illustrative purposes only and form no part of the claimed design.
